UNITED STATES PATENT OFFICE.

HERBERT E. KEELER, OF NEW YORK, AND HARRY L. DUNCAN, OF BROOKLYN,
NEW YORK; SAID DUNCAN ASSIGNOR TO SAID KEELER.

CURTAIN-FIXTURE.

SPECIFICATION forming part of Letters Patent No. 689,195, dated December 17, 1901.

Application filed August 9, 1901. Serial No. 71,483. (No model.)

To all whom it may concern:

Be it known that we, HERBERT E. KEELER, a resident of the city and county of New York, and HARRY L. DUNCAN, a resident of Brooklyn, county of Kings, State of New York, have invented new and useful Improvements in Curtain-Fixtures and Processes of Making the Same, of which the following is a specification, taken in connection with the accompanying drawings, in which the same reference characters refer to similar parts in the several figures.

This invention relates to curtain-fixtures which are adapted to be applied to curtains more especially used in car-windows, so that such curtains may be readily raised or lowered and may be held securely in any desired position.

Figure 1 is a front side view of this fixture as applied to a curtain. Fig. 2 is a horizontal sectional view through the fixture. Fig. 3 is a front view of part of the fixture. Figs. 4 and 5 are transverse sectional views, on a larger scale, taken on the lines 4-4 and 5-5 of Fig. 2. Figs. 6 to 9 indicate the method of assembling this fixture. Figs. 10 to 14 show details on a larger scale.

The curtain A, of any suitable flexible material, is formed with a fringe or bottom A², so that it may be readily grasped for the purpose of raising or lowering it. The pocket A', formed near the bottom of the curtain, serves to support the tube B, formed of iron or other suitable rigid material. This tube should extend substantially the whole width of the curtain. This tube is formed with an elongated tube-opening near the center of the tube, extending along one side of the same. This tube-opening comprises an elongated tube-slot B² and also a tube-notch B³, which when the fixture is assembled is in the center of the opening A³ in the pocket of the curtain.

Upon the front of the curtain-pocket is rigidly secured the escutcheon C, having, if desired, sharp inwardly-projecting points at its corners to more firmly engage the curtain and formed of sheet metal—such as, for instance, brass. It is formed with the escutcheon-slot C', extending longitudinally of the tube, also with the escutcheon-notch C², which registers

with the tube-notch B³ directly below it, and also with the handle-opening C³, as is shown in Fig. 10. The center block D is rigidly secured in position, passing through the escutcheon-notch and the tube-notch, by means of the screw D², which engages the threaded hole B⁴, formed in the rear side of the tube. This screw serves to hold all of these parts in proper position, clamping the escutcheon and tube firmly together and securing these parts to the curtain. It will be noted that the center block is formed with the outwardly-projecting lugs D', which serve to engage the escutcheon, as is shown in Fig. 4, and this block is suitably perforated with the hole D³ for the screw D². The center block may be formed with a cover-plate D⁵, preferably integral with the same, as indicated in Figs. 4 and 14, to cover the handle-opening C³. The center block may be formed as is indicated in Figs. 12 and 13, in which the block is formed of a flat metal plate having a central depressed portion with a hole D⁶ in the same and having the flanges D⁷ formed on either side of this depressed portion. The cover-plate D⁵ extends over the handle-opening in the escutcheon, as is indicated in Fig. 12. When assembled, the depressed portion of the center block engages the escutcheon-notch and holds the escutcheon in proper position with respect to the tube. If desired, the center block having a cover-plate may be formed to engage both the escutcheon-notch and the tube-notch to hold these parts more rigidly in position.

Within the tube are the rods E, which in this curtain-fixture are preferably rigidly and permanently secured to the handles E³, although the rods may be connected to the handles in any desired way to make a firm connection between these parts while they are in operation. The shoulders E', formed, if desired, on these handles, engage the inner surface of the tube and are guided thereby as they reciprocate along the tube. The handles adjacent the shoulders, as indicated by E², engage the tube-slot B² and are guided thereby as the handles reciprocate in the tube. It will be noted also by reference to Fig. 5 that the escutcheon-slot C', and also the opening in the curtain-pocket, are formed wider than

the tube-slot at this point, so that the handles are free from the escutcheon and curtain and are guided by the tube-slot. Instead of this construction it may be desirable in some cases to form the escutcheon - slot so that it will be of the same width as the tube-slot, or even narrower in some cases, so that the escutcheon - slot may act as the guide for the handles in their reciprocation.

- 10 To each one of the rods E is secured a guiding member G, which engages a suitable vertical guide and serves in this way to guide the lower end of the curtain in its movement, as is well known in this art. As is seen by 15 reference to Fig. 2, the spindle F, attached to each guiding member or foot, is formed with a threaded hole F', and the end of the rod at E' is threaded and engages the hole F'. The foot therefore may be adjusted in position by 20 this means relative to the rod on which it is mounted, so that the distance between the feet of this fixture may be readily adjusted to properly engage the guide. Each foot is 25 pressed outward by a spring E⁵, this spiral spring engaging the inner end of the foot-spindle F and also the internal collar B', formed on the tube, as is indicated. The foot is composed of the cross-head, integral with the spindle F and carrying at its outer extremities 30 the pivots F³, upon which the rolls F² are mounted. The casing G has rigidly secured to the same the pivot F⁴, which is mounted in a suitable bearing in the cross-head, as indicated in Fig. 1, so that the casing may turn 35 about at this point. Rigidly secured to the casing G is the friction - shoe G', extending nearly the whole length of the foot and bearing against the guide in which the foot runs. The shoe ends G², preferably turned outward 40 slightly at their extreme outer portions, are also rigidly secured to the casing G and are adapted to bear against the guide. As will be noted by reference to Fig. 2, the side plates of the casing G also bear on the guide, and 45 in some cases it may be desirable to omit the friction-shoe G', since a sufficient frictional bearing would be obtained by the shoe ends and by the side plates of the casing G, which engage the guides. In some cases the side 50 plates may be formed so as not to engage the guide. The openings G³ between the shoe ends and the friction-shoe G' are formed to allow the rolls F² to come in contact with the guide in case the fixture is tilted from its proper 55 horizontal position. In such a case as soon as the fixture has been displaced from proper horizontal position in the guides sufficiently to bring the rolls in contact with the guides the very slight friction of these rolls against 60 the guides at once allows the shade-roll to which the curtain is attached, as is well known in this art, to raise the fixture on the side which is farther down, so as to at once automatically restore the fixture to its proper horizontal position. As soon as this occurs the 65 friction-shoes and shoe ends are restored to contact with the guides, and the roller is no

longer sufficiently strong to move the fixture against the friction caused by the springs E⁵. It will be noted that this form of self-righting foot is very desirable, since the casing G serves to entirely cover the rolls and cross-head and also since the shoe ends, which may, if desired, be formed longer than is indicated in the drawings, serve to readily give a long frictional contact with the guide, since the shoe ends project beyond the rolls. Instead of this form of foot, however, a simple friction-foot, such as is indicated in Fig. 9, may be employed. In this case the spindle F⁶, 80 provided with the threaded hole F', as indicated, is rigidly secured to a simple friction-foot F⁸, formed of one piece of material, such as brass, and upturned at the ends to properly engage the guides. 85

This curtain-fixture is assembled as follows: The curtain-pocket is formed in the lower end of the curtain and the opening A³ cut in the center part of this pocket. A tube B is inserted into the pocket, as is indicated in Fig. 90 6, so that the end of the tube-slot B², which, as is shown, is considerably longer than the opening A³ in the pocket, comes into alignment with the end of the opening in the pocket. The rod E is then inserted from the side of 95 the opening A³ which is in alignment with the end of the tube-slot into the tube, as indicated, the rod displacing the flexible material of the pocket, as indicated in this figure, or since the rod is usually of flexible material the rod may bend sufficiently to allow the ready insertion of the rod into the tube. The internal collars B' on the tube B are 100 formed with a tapering inner surface, as is indicated, so that the end of the rod E is guided past these collars as the rod is inserted. Then when the shoulder E' slips down into the opening A³ the tube is pushed into a central position, as shown in Fig. 7, and the shoulder is 105 then inserted through the tube-notch B³ into its position within the tube. The tube is now pushed in the other direction, so that the opposite ends of the pocket-opening A³ and the tube-slot B² come into alignment, the handle being pressed to this end of the slot, as indicated in Fig. 8. The second rod E is now inserted, as indicated in that figure, in a manner similar to the first rod, the shoulder E' being slipped around the handle E³ first inserted, so that the shoulder drops down into the 110 opening A³ in the pocket. Thereupon the tube is restored to the central position (indicated in Fig. 9,) the shoulder E' being inserted into the tube-notch B³ to its central position within the tube. The handles E³ are now pressed together and the escutcheon put in position 115 by passing the handles through the handle-opening in the escutcheon. The handles may now be separated and the escutcheon clamped in final position upon the fixture by 120 the center block, which, as has been described, holds the tube and escutcheon firmly in position on the curtain. The feet are now 125 screwed upon the rods at either end of the

fixture, the springs having been previously inserted, and the feet are adjusted into proper position, so as to engage the guide-grooves to the desired extent.

5 Numerous modifications may be made by those skilled in the art and without departing from the spirit of this invention. We do not, therefore, wish to be limited by the disclosure which we have made in this case; 10 but what we wish to secure by Letters Patent is set forth in the appended claims.

What is claimed as new is—

1. In a curtain-fixture, a curtain having a pocket formed at its lower portion, there being an opening formed in the side of the curtain communicating with said pocket, a tube having an elongated tube-slot formed therein and a central tube-notch, rods having handles permanently secured thereto to be inserted into said tube through said tube-slot, an escutcheon formed with an escutcheon-slot, with an escutcheon-notch and with a handle-opening, and a center block formed with a cover-plate to cover said handle-opening and clamped in position in engagement with said escutcheon-notch to secure said escutcheon in alinement with respect to said tube, and a shoe-spindle having a threaded connection with each of said rods to adjust the position of said shoe upon said rod, springs to force said spindles outward, a casing pivotally connected to said spindle, a friction-shoe and shoe ends secured to said casing to frictionally engage a guide, a cross-head formed on said shoe-spindle and rollers pivoted to the ends of said cross-head to project between said friction-shoe and said shoe ends to form a self-righting foot.

2. In a curtain-fixture, a curtain formed with a pocket in its lower portion, there being an opening in said curtain communicating with said pocket, a tube formed with an elongated tube-slot and with a tube-notch, rods permanently secured to handles to be inserted into said tube through said curtain-opening and said tube-notch, shoulders formed on said handles to be guided by said tube-slot in reciprocating longitudinally of said tube, an escutcheon formed with an escutcheon-slot, an escutcheon-notch and a handle-opening and a center block formed with a cover-plate to be clamped in position in said escutcheon-notch by a screw engaging said tube, a friction-foot having a screw connection with each of said rods to adjust the position of said foot, and springs to force said feet outward.

3. A curtain-fixture, a curtain formed with a pocket extending across the lower end of the same, there being an opening communicating with said pocket, a tube inserted in said pocket, there being a tube-notch and an elongated tube-slot formed in said tube, rods having handles permanently secured to the same to be inserted into said tube through said opening and said tube-notch, an escutcheon formed with an escutcheon-slot, an escut-

eon-notch and a handle-opening, a center block engaging said escutcheon-notch and said tube-notch and secured to said tube to clamp said escutcheon in position, friction-feet adjustably secured to said rods and means to yieldingly press said friction-feet outward.

4. In a curtain-fixture, a curtain, a pocket formed across said curtain near one end of the same, there being an opening formed in said curtain communicating with said pocket, a tube in such pocket, an elongated tube-opening in said tube, rods having handles permanently secured to the same to be inserted into said tube through said opening in said curtain and said tube-opening, an escutcheon-plate formed with an escutcheon-slot, means to secure said escutcheon to said tube to hold said escutcheon in position, friction-feet secured to said rods and means to press said friction-feet outward.

5. In a curtain-fixture, a tube formed with an elongated tube-opening, rods having handles permanently secured thereto to be inserted into said tube through said tube-opening, guiding members secured to said rods and means to press said rods outward.

6. In a curtain-fixture, a tube having a tube-opening formed near the center of the same, rods having handles permanently secured thereto to be inserted into said tube through said tube-opening, guiding members adjustably secured to said rods, and means to press said rods outward.

7. In a curtain-fixture, a tube formed with a tube-slot and a tube-notch therein near the center portion of said tube, rods having handles permanently secured to the same and having shoulders formed on said handles to be inserted into said tube through said slot, said shoulders entering said tube through said notch and being guided within said tube in reciprocating longitudinally of the same, guiding members secured to said rods and means to force said rods outward.

8. In a curtain-fixture, a tube formed with an elongated tube-slot and with a tube-notch near the center portion of the same, rods having handles permanently secured to the same to be inserted into said tube through said slot, an escutcheon formed with an escutcheon-slot, an escutcheon-notch, and with a handle-opening, a center block having a cover-plate secured thereto engaging said escutcheon-notch and said tube-notch to hold said escutcheon in position and guiding members adjustably secured to said rods.

9. In a curtain-fixture, a shoe-spindle, a cross-head formed integral with said spindle, rollers pivoted to the ends of said cross-head, a casing pivotally connected to said cross-head, a friction-shoe and shoe ends secured to said casing, said rollers being mounted to project between said friction-shoe and said shoe ends.

10. In a curtain-fixture, a shoe-spindle, a cross-head secured to said spindle, rollers

- mounted in said cross-head, a casing inclosing said cross-head and pivoted to said cross-head near the center of the same, shoe ends secured to said casing to frictionally engage a guide, there being openings in said casing through which said rollers may project into contact with said guide.
11. In a curtain-fixture, a spindle, a cross-head secured to said spindle, rollers mounted at the ends of said cross-head, a casing inclosing said cross-head and pivotally secured to the center of said cross-head and shoe ends secured to said casing beyond said rollers, the side members of said casing and the shoe ends engaging a guide.
12. In a curtain-fixture, a shoe-spindle, a cross-head secured to said shoe-spindle carrying rollers at its outer ends, a casing inclosing said cross-head and pivoted to said cross-head, shoe ends formed on said casing to engage a guide beyond said rollers, there being openings in said casing through which said rollers may project into contact with said guide.
13. In a curtain-fixture, a spindle, a cross-head secured to said spindle, antifriction members mounted at the ends of said cross-head, a casing inclosing said cross-head and movably mounted on said cross-head, shoe ends secured to said casing to engage a guide beyond said antifriction members, there being openings in said casing through which said antifriction members may project into contact with said guide.
14. In a curtain-fixture, a cross-head, rollers mounted in said cross-head, a casing inclosing said cross-head and pivotally connected to the center of the same, shoe ends secured to said casing to frictionally engage a guide, there being openings in said casing through which said rollers may project into contact with said guide.
15. In a curtain-fixture, a cross-head, rollers mounted at the ends of said cross-head, a casing inclosing said cross-head, said cross-head being pivotally secured to the center of the same and shoe ends secured to said casing beyond said rollers, the side members of said casing and the shoe ends engaging a guide.
16. In a curtain-fixture, a tube formed with an elongated tube-opening, a rod having a handle permanently secured thereto to be inserted into said tube through said tube-opening, a guiding member secured to said rod, means to press said rod outward and a guiding member mounted in the opposite end of said tube.
17. In a curtain-fixture, a tube formed with a tube-slot and a tube-notch therein near the center of said tube, a rod having a handle permanently secured to the same and having a shoulder formed on said handle, to be inserted into said tube through said slot, said shoulder entering said tube through said notch and being guided within said tube in reciprocating longitudinally of the same, a guiding member secured to said rod, a guiding member connected with the opposite end of said tube and means to force said rod outward.
18. In a curtain-fixture, a curtain formed with a pocket extending across the lower end of the same, there being an opening communicating with said pocket, a tube inserted in said pocket there being an elongated tube-opening formed in said tube, a rod having a handle permanently secured to the same to be inserted into said tube through said openings, a guiding member secured to said rod, a guiding member connected with the opposite end of said tube, and means to force said rod outward.
19. The process of assembling the parts of a curtain-fixture and of connecting the same to a curtain, which consists in inserting a tube having a tube-opening into the pocket of a curtain having an opening adapted to register therewith, in inserting into the tube through the registering openings rods having handles secured thereto, and in connecting guiding members with said rods at the outer ends of said tube.
20. The process of assembling the parts of a curtain-fixture and of connecting the same to a curtain, which consists in inserting a tube having a tube-opening near the central part of the same into the pocket of a curtain having an opening near the central part of the same adapted to register therewith, in inserting into the tube through the registering openings rods having handles secured thereto, in securing an escutcheon-plate to said curtain and said tube by a center block, and in connecting guiding members with said rods at the outer ends of said tube.
21. The process of assembling the parts of a curtain-fixture, which consists in inserting rods having handles connected thereto into a curtain-tube having a tube-opening near the center of the same through said opening, and in connecting guiding members to said rods at the outer ends of said tube.
22. The process of assembling the parts of a curtain-fixture which consists in inserting a rod having a handle secured thereto into a curtain-tube having a tube-opening near the center of the same through said opening, in connecting a guiding member to said rod at the outer end of said tube and in mounting a guiding member at the opposite end of said tube.
